(57) CLAIM

The ornamental design for a utensil handle, as shown and described.

DESCRIPTION

FIG. 1 is a side, top perspective view of the utensil handle showing our new design, the broken lines showing the attached neck, spoon portion and aperture in the handle are for illustrative purposes only and form no part of the claimed design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.
